UNITED STATES PATENT OFFICE.

HANS E. HELLER, OF STOCKTON, CALIFORNIA.

JUMBO FOR TUNNEL FORMS.

Application filed June 2, 1926. Serial No. 113,303.

This invention relates to the tunneling art; and particularly to a device for manipulating the sectional metal forms used in tunnels when the same are to be lined with concrete, as is now very frequently done.

The principal object of my invention is to provide a jumbo to be used in connection with a collapsible or jointed sectional form to engage, support and transport the section when it is desired to shift the same; and so constructed that the services of only a single man, or at the most two men, are necessary to operate the jumbo even when the latter is supporting a large and heavy form section.

With this jumbo, in connection with the simple jointed form-section used, it is possible to advance the forms or sections as required with great speed and small loss of time, enabling lining operations to be carried out at a minimum of cost and in very quick time.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of my improved jumbo shown in connection with a fragmentary portion of sectional form.

Fig. 2 is an end elevation of the jumbo shown in engaged position with the form.

Referring now more particularly to the characters of reference shown on the drawings, the forms used in connection with my jumbo are substantially of horseshoe shape in cross section. The form consists of a number of sections to be longitudinally aligned with each other, each section comprising transverse top frames 1 spaced apart longitudinally, and side frames 2 depending from the top frames to form a continuous outline of the desired shape. The frames 1 are hinged to the frames 2, so that the latter can swing inwardly from their normal position, by longitudinal rods 3 which extend through all the frames 1 and 2. Plates 4 are secured to and connect the various frames 1 and 2 on the outside of the same to form a solid continuous covering. Said plates of course

are separated longitudinally along the hinge lines of the members 1 and 2.

Horizontal flat bars 2^a extend between the members 2 along the bottoms thereof. In setting a section up in the tunnel, mud sills 60 are set along the bottom of the tunnel, the bars 4 resting thereon. These bars are temporarily spiked to the sills. Wedges 6 are then placed under the sills at intervals so that each form-section may be supported in exact alinement with adjacent sections. The end frames 1 and 2 of each section are provided with a series of holes 7, so that bolts may be removably placed through the abutted frames of adjacent sections to temporarily fasten the same together.

My improved jumbo to be used in supporting and transporting a section along the tunnel as lining operations proceed, comprises a main bed or frame 8, built up of suitable material and in a rigid manner. Said frame is supported by longitudinally spaced wheels 9 which ride on rails 10 laid on ties 11 which rest on the bed of the tunnel.

Supported by and projecting upwardly from the frame 8 are longitudinally spaced toggle-joint structures. Each such structure comprises lower arm members 12 and upper arm members 13, arranged as transversely separated pairs suitably braced together to form rigid units. The lower arm units are pivoted in common onto the frame 8 as at 14 and diverge longitudinally of the jumbo toward their upper ends. The upper arm units are pivoted in common with the upper ends of the arms 12 and converge toward their upper ends. At said upper ends the arms 13 are pivoted in common as at 15 onto a horizontal frame which includes longitudinally extending beams 16. These beams at their ends and close to the pivots 15 support transverse overhanging beams 17, the latter being preferably reinforced vertically by gusset plates 18. The upper ends of the lower arm units and the lower ends of the upper arm units are pivotally connected together by means of transverse blocks 19 extending between corresponding pairs of arms, the blocks having lateral trunnions 20, which form pivotal pins as well as connecting means for said arms.

A longitudinal shaft 21 extends through all the blocks, with crank handles 22 at its ends. This shaft is threaded through the blocks, the threading for the blocks of each

toggle joint structure being right and left hand. Therefore when the shaft is turned one way or the other, the arms of the toggle joints will approach or move away from each other at their pivotal connections 20, causing the upper ends of the arms 13 and the frame 16 to be raised or lowered accordingly. Since both toggle joints are identical in size, and they are connected in common by the single operating shaft 21, both structures will move to the same extent and the vertical movement of the frame 16 will be uniform at both ends, and parallel to a horizontal plane.

15 In operation the frame 16 is first lowered by manipulation of the shaft 21 so that the outer ends of the beams 17 clear the form frame members, allowing the jumbo to be moved longitudinally through the tunnel without interfering with the form sections. When the jumbo has arrived at and under the section to be shifted, the frame 16 is raised so that the beams 17 rest on the longitudinal rods 3 of the form. The spacing of 25 the beams 17, and the position of the jumbo relative to the form, is such that the engagement of said beams with the rods 3 will be at points close to certain ones of the form frames, so as to prevent deflection of the rods. The rods are then held against lateral slipping on the beams 17 by hooks 23 mounted on said beams and arranged to detachably engage said rods.

Assuming that the bolts that fasten adjacent form sections to each other have been removed, as well as the spikes holding the bars 2^a to the mud sills; the shaft 21 is then rotated to further raise the frame 16, causing the beams 17 to rest firmly against rods 3. Then upon releasing the wedges 6, the mud sills 5 may be lowered sufficiently to enable the frames 2 to swing inwardly. The form supporting elements of the jumbo are then lowered until the upper form frame 1 is entirely clear of the frame of an adjacent form section, as shown in dotted lines in Fig. 2.

The jumbo with the form section supported therein, is then moved along the tunnel inwardly of the other form sections until it has arrived at the location where said section is again to be set up. The form supporting elements of the jumbo are then again raised to place the section at the proper height and so that the frames 2 can be swung outwardly to overhang the sills. The form is then lowered until said frames 2 rest on the sills, when the beams 17 of the jumbo may be lowered still further to cause 60 said beams to clear the section. The final

lining up of the form section relative to an adjacent section is then done by manipulation of the wedges 6. Owing to the use of the toggle arm and screw structure, a very powerful appliance is provided, which may be easily manipulated by one or at the most 65 two men operating the handles 22.

From the foregoing description it will be readily seen that I have produced such a device as substantially fulfills the objects of 70 the invention as set forth herein.

While this specification sets forth in detail the present and preferred construction of the device, still in practice such deviations from such detail may be resorted to as do 75 not form a departure from the spirit of the invention, as defined by the appended claims.

Having thus described my invention what I claim as new and useful and desire to secure by Letters Patent is:

1. In combination, a tunnel form-section including transverse top frames, side frames depending therefrom and longitudinally extending rods pivotally connecting the side and top frames; a wheel supported frame movable along the tunnel under the top frame and inwardly of the side frames, and vertically movable means on said movable frame for detachably engaging said rods to cause the weight of the form-section to be 80 supported by said means.

2. In combination, a tunnel-form section including transversely extending top frames, and longitudinally extending rods adjacent the ends of said frames; and a jumbo for manipulating the form including a wheel supported frame movable under the form, raising and lowering means on said wheel frame, and transversely extending beams carried by said means for direct but detachable supporting engagement with the rod members.

3. A structure as in claim 2, with catch means mounted on the beams for detachable engagement with the rods to prevent lateral movement of the rods and form relative to the jumbo.

4. In combination, a tunnel-form section including transversely extending top frames, a jumbo for manipulating the form including transverse beams disposed under the form, and means for raising and lowering the beams; and members mounted in connection with the form frames at the sides thereof positioned to detachably rest directly on the beams adjacent their ends when said beams are raised.

In testimony whereof I affix my signature.

HANS E. HELLER.
